United States Patent Office

Des. 209,073
Patented Oct. 31, 1967

209,073

CARAFE

Gene Martin, 616 Richmond Road
East Meadow, N.Y. 11554

Filed Aug. 1, 1966, Ser. No. 3,300

Term of patent 14 years

(Cl. D44—21)

FIG. 2 is a side elevational view thereof,

FIG. 3 is a bottom plan view thereof,

FIG. 4 is a front elevational view thereof, and

FIG. 5 is a top plan view with the cover turned.

I claim:

The ornamental design for a carafe, substantially as shown.
